SECURITY LOCK

Eduard Schmidt, New York, N. Y.

Application September 17, 1932, Serial No. 633,580

2 Claims. (Cl. 70—75)

This invention relates to locks and more particularly to locks of the lever tumbler type adapted for doors and like objects whereby they may be securely held when in closed position.

5 One of the objects of the invention is to provide a lock which can be operated from both sides by a key having two different kinds of bits on the same stem.

A further feature is in the provision of means 10 within the lock casing which prevents opening of the lock with a false key.

Another purpose is to produce a lock operable from one side by a key incapable of operating from the other side.

15 These important purposes are accomplished by the novel construction and combination of parts hereinafter described and illustrated in the accompanying drawings, constituting a material component of this disclosure, and in which:—

20 Figure 1 is a side elevational view of an embodiment of the invention, the cover plate being omitted.

Figure 2 is a similar view from the opposite side of the lock.

25 Figure 3 is a side elevational view of a specific form of the key used in connection with the lock.

Figure 4 is a transverse sectional view taken on line 4—4 of Fig. 3.

Figure 5 is a similar sectional view taken on line 30 5—5 of Fig. 3.

Figure 6 is an enlarged transverse sectional view of the lock taken on line 6—6 of Fig. 1.

Figure 7 is a longitudinal sectional view taken on line 7—7 of Fig. 1.

35 Figure 8 is a fragmentary sectional view of the lock casing showing the bolt in a retracted position, the section being taken on line 8—8 of Fig. 6.

Figure 9 is a similar view taken on line 9—9 of 40 Fig. 6, showing the opposite side of the bolt.

Figure 10 is another like view looking on line 10—10 of Fig. 6.

Figure 11 is a view similar to Fig. 9, but showing the bolt in an outward position.

45 Referring in greater detail to the drawings the lock casing is shown to be comprised of a back plate 15, generally rectangular in profile.

A face plate 17 connects between side walls 18—19 integral with a rear-wall 20, these walls 50 being of materially lesser height than the face 17.

A cover plate 21 completely covers the walls 18—19 and is secured by screws in the usual manner to studs projecting inwardly from the plate 15.

55 A bolt 22, slidable in the casing to be project-

ed through an opening in the face plate 17 is provided with a ledge 23 limiting its outward movement by contact with the plate.

The shank of the bolt contains a central longitudinal recess 24 in which operates a pivoted plate 25 pivoted on a stud 26 set in upper and lower elements respectively 27—28 of the shank, and through which are formed longitudinal registering slots, 29—30.

A rectangular stud 31, fixed in the back plate 15, engages the side edges of the slots to act as a guide for the bolt, and also extends upwardly through the cover plate 21.

The stud 31 also passes through a corresponding slot 32 in the pivoted plate 25, this latter slot being straight at its rear edge which is maintained normally against the stud by a flat spring 52 fixed in plate 25, which is further provided with three spaced notches 33—34—35 in its front edge, these notches being curved with a radius 70 struck from the stud 26, permitting the plate 25 to swing in the manner indicated in Figs. 10 and 11.

Plugs 36 are fixed in pivoted plate 25 to extend equally through both sides, to maintain 80 the pivoted plate centrally of the bolt shank elements 27—28 and tend to prevent sticking by contact of the superficial areas.

In the rear edge of the shank element 27 are three notches 37—38—39, and in the mating element 28, are similar notches, 37'—38'—39', all corresponding in distances apart to the wing notches 33—34—35.

Engageable in the notches of the lower bolt shank element 28 is the hooked end of a tumbler 90 40, its opposite end being looped around a post 41 fixed in the front portion of the casing, the tumbler being pressed into engaging position by a flat spring 42 coiled about a rectangular stud 43 fixed in the casing, see Fig. 1.

In a similar manner an opposed tumbler 44 has a hooked end to engage the notches 37—38—39 in the shank element 27, the opposite end of the tumbler being looped around a post 45 fixed in the rear portion of the casing and pressed 100 into engagement by a flat spring 46 coiled about a square stud 47 fixed in the casing.

Carried by the tumbler 40 is an inreaching flat plate 48, disposed between the lower surface of the shank element 27 and casing back plate 15, 105 and having a cam-like opening 49.

A similar flat plate 50 is carried in a like manner by the tumbler 44 to be disposed between the upper surface of the shank element 27 and under side of the partial cover plate 21, the 110

plate 50 having an elliptical cam-like opening 51.

The width of the bolt shank element 28 is materially less than that of the mating element 27 and formed in its edge, opposite the notches 5 37'-38'-39' are ward recesses 55-56 having angularly bevelled entrances.

Similar ward recesses 57-58 are formed in the corresponding edge of the upper element 27, these recesses registering longitudinally of the bolt but are not in lateral registration due to the different widths of the shank elements and serve a purpose later on apparent.

Formed in the back plate 15 is a key hole 60 having a circular portion 61 from which leads 15 a slot 62 having two lateral notches 63-64 on one side and three lateral notches 65-66-67 on the other, the foot of the key hole being arcuate.

A similar key hole 70 is formed in the partial cover plate 21, in register with the key hole 60, 20 as may be seen in Figs. 1 and 2.

Set rigidly in the plate 21 is a key guide 68 open at 69 to admit passage of the bits of the key by which the lock is controlled.

This key, shown in Figs. 3, 4 and 5, consists of 25 a round shank 72, preferably having a knurled central portion, the shank being uniform in diameter and provided with ornamental rounded ends 73-74.

Adjacent to the end 73 are two spaced bits 20 75-76 respectively outer and inner, the outer bit 75 being in excess of the length of the inner bit. On the bit 76 is a single ward 77 midway its length adapted to pass through the recess 67 of the key hole 60, and opposed end wards 78-79 to pass the recesses 63-66.

A space 80 separates the bit 76 from the outer bit 75, which latter is provided with a single ward 81, registering with the ward 77 and two outer opposed wards 82-83 to pass the recesses 48 64-65.

At the opposite end portion of the key are two similar bits 75'-76' having a space 80' therebetween and arranged in a reversed position relative to the shank 72.

45 It will now be understood that one end of the key is used from the inner side of the lock, through the key hole 60 and the other end through the key hole 70 as directed by the guide 68.

50 In operation, the bolt being in a retracted position, as shown in Figs. 3, 9 and 10, and it being desired to move the bolt into a locked position from the inner side, as represented by the key hole 60, the key end 74 is inserted and given 55 the usual partial rotary movement.

The bit 75' presses the tumbler plate 50 outwardly, against the spring 46, removing the tumbler 44 from the bolt notch 37; coincidentally the bit 76 acts in a similar manner with respect 65 to the tumbler plate 48, spring 42 and tumbler 40, releasing it from the bolt notch 37', thus freeing the bolt.

The bit 75', during turning the key, engages the bolt recess 57, while the bit 76' engages the corresponding bolt recess 55, thereby urging the bolt outwardly.

It will be apparent that the lock may be operated from the other side by reversing the key and inserting it into the lock through the guide

68, whereupon the bolt may be actuated in a similar manner.

The use of a spurious key is prevented by the pivoted plate 25, which is moved outwardly, engages the fixed post 31 in any of its several recesses, preventing movement of the bolt, while, due to the spaces 80-80', a proper key may be used without causing movement of the plate 25.

When the bolt has been fully extended the same is positively held by re-engagement of the tumblers in the bolt shank notches, requiring the use of a proper key to unlock as well as to lock the device.

Thus it is apparent that normally the bolt bar is held against movement in the case by both of the master tumblers 48 and 50 and the anti-pick tumbler 25 is in inoperative position. It is also apparent that any instrument or key inserted into the lock from either side and so manipulated as to displace the anti-pick tumbler 25 will positively prevent the bolt bar being moved in the case even though the operator has succeeded in releasing the tumblers 48 and 50 from the bolt bar and engaging the bar.

As changes of construction could be made 100 within the scope of the claims, it is intended that all matter contained in the foregoing description or shown in the accompanying drawings shall be interpreted as illustrative and not in a limiting sense.

Having thus described the invention, what is claimed as new and desired to secure by Letters Patent, is:—

1. In a lock of the character described, a case, a bolt bar movable therein and having a plurality of key-engageable portions spaced different distances from the longitudinal center line of the bolt bar, whereby a certain key bit arrangement fits said key-engageable portions when presented from one side of the bolt bar and a reverse key bit arrangement fits said key-engageable portions when presented from the opposite side of the bolt bar.

2. In a lock of the character described, a bolt bar having a shank including two laterally spaced 120 wall portions of unequal width, the edge of one wall portion being disposed outwardly of the corresponding edge of the other wall portion, and each having key-engageable shoulders at said edges, said wall portions at their other edges 125 having tumbler notches, tumblers engageable with said walls at said notches, an anti-pick tumbler disposed between said wall portions, pivoted on the bolt bar and having an edge disposed outwardly of the base of said key-engaging shoulders, a post secured to the case positioned to be engaged by the anti-pick tumbler, when depressed between said wall portions, to lock the bolt bar against movement, and said bolt bar being movable by means of a key adapted to be inserted into the case and having bits adapted 130 to depress the master tumblers to release the bolt bar and to engage the key-engageable shoulders to move the bolt bar, and having a recess adapted to receive the anti-pick tumbler to avoid displacing the anti-pick tumbler to lock the bolt bar.

135 3. In a lock of the character described, a bolt bar having a shank including two laterally spaced wall portions of unequal width, the edge of one wall portion being disposed outwardly of the corresponding edge of the other wall portion, and each having key-engageable shoulders at said edges, said wall portions at their other edges having tumbler notches, tumblers engageable with said walls at said notches, an anti-pick tumbler disposed between said wall portions, pivoted on the bolt bar and having an edge disposed outwardly of the base of said key-engaging shoulders, a post secured to the case positioned to be engaged by the anti-pick tumbler, when depressed between said wall portions, to lock the bolt bar against movement, and said bolt bar being movable by means of a key adapted to be inserted into the case and having bits adapted to depress the master tumblers to release the bolt bar and to engage the key-engageable shoulders to move the bolt bar, and having a recess adapted to receive the anti-pick tumbler to avoid displacing the anti-pick tumbler to lock the bolt bar when the key is manipulated in the case.

EDUARD SCHMIDT.
